GOLF CLUB

Dominick U. Belline, Great Neck, and
Frank S. Strafaci, Flushing, N. Y.

Application April 20, 1950, Serial No. 9,362

Term of patent 14 years

(Cl. D34—5)

To all whom it may concern:

Be it known that we, Dominick U. Belline and Frank S. Strafaci, citizens of the United States and residents respectively of Great Neck, county of Nassau, State of New York, and Flushing, county of Queens, and State of New York, have invented a new, original, and ornamental Design for a Golf Club, of which the following is the specification, reference being had to the accompanying drawing forming a part thereof.

Figure 8 is a sectional view taken along the line 8—8 of Figure 7 but in the direction of the arrows.

We claim:

The ornamental design for a golf club, substantially as shown.

DOMINICK U. BELLINE.
FRANK S. STRAFACI.
